UNITED STATES PATENT OFFICE.

WILLIAM J. SLOAN, OF CLEVELAND, OHIO, ASSIGNOR OF ONE-HALF TO FRANK PAULIN,
OF CLEVELAND, OHIO.

WALL RECEPTACLE FOR RECEIVING DELIVERIES.

Application filed November 22, 1918. Serial No. 263,657.

To all whom it may concern:

Be it known that I, WILLIAM J. SLOAN, a citizen of the United States, and resident of Cleveland, in the county of Cuyahoga and State of Ohio, have invented certain new and useful Improvements in Wall Receptacles for Receiving Deliveries, of which I hereby declare the following to be a full, clear, and exact description, such as will enable others skilled in the art to which it appertains, to make and use the same.

The objects of the invention are to provide a wall receptacle in which fresh milk or cream, or other commodities, can be deposited by the delivery man, and which is provided with inside and outside doors, and when the outside door is closed from the outside, it cannot be opened from without, but can be only released from the inside or by closing the inside door, and when the inner door is closed, it cannot be opened from without for the reason that a separate bolt or catch can be employed to retain the same.

The invention comprises locking mechanism for the outer door, which is releasable only by closing the inner door, or from the inside of the house, and it is automatically locked by closing the outer door. In this matter the entrance to the house is protected in case the opening should be large enough to permit a thief to crawl through. The invention consists in a latch member pivoted in the frame of the receptacle and operated by the movements of the inner door in closing the same to engage a catch or keeper on the inner face of the outer door and includes a guard member on the outer door which prevents engagement of the latch and keeper after they have been separated by closing the inner door, until the outer door has been opened, but when the outer door is afterwards shut, it will be locked in place.

The invention is illustrated in the accompanying drawing, hereinafter more fully described and particularly pointed out in the claim.

In the accompanying drawings Fig. 1 is a perspective showing the interior of the wall casing, and the operating means upon the inner and outer doors; Fig. 2 is a similar view showing a modified form of latch.

Fig. 3 is a perspective of the latch upon the inner door.

Fig. 4, is a side elevation of the latching parts shown on the inner door.

In these views, in Fig. 1, A is a spring pressed latch pivoted in the side wall of the casing and having its extremities bent at an angle thereto at A' and A² respectively. When the outer door B is closed, the extremity A² will first rise upon the catch B' and then fall and engage with same, and pivoted guard B² will fall upon it. When the inner door C is closed, a plate C', pivoted at C² thereon will then engage the extremity A' of the latch and turn it upon its pivot or axis and will lift the locking extremity A² out of its keeper B' and release the outer door. A stop C³ prevents movement of the plate C' as the door closes and the pivot permits it to pass the latch on the return movement when the extremity A' is forced down to the horizontal position, the pivoted plate C' will pass over and beyond it and release the extremity A'.

The inner door is always closed at night, and the milk man will always find the outer door released so that he can insert the milk or cream into the casing, and he immediately closes the door, which automatically locks itself by the engagement in a horizontal direction of the latch extremity A² with the keeper B' as soon as the door is shut. The latch will then automatically raise the guard and pass under it.

It will be observed that when the outer door is shut the latch extremity A² will be automatically raised by the catch B' and dropped into engagement with the catch B', thus enclosing the milk jar in the casing. When the inner door is shut, the depending hinged plate C' will engage the outer end of the latch A' and raise the latch and release the latch extremity A' from the catch B', so that the outer door can be opened. The guard B² will then fall down over the catch B' and prevent the latch from engaging with the same until the outer door has been opened, but when the outer door is closed again, the latch A² will raise the guard and again engage with the catch, and lock the outer door until the inner door is opened to remove the milk jar and is closed again, when the outer door will be again released.

In Fig. 2 the operation is similar, but the latch is pivoted to swing instead of rotate, and D is a latch pivoted at D' intermediate of its ends, upon the side of the frame. The catch D² upon the outer door is sub-

stantially the same as that shown in Fig. 1 and the pivoted guard D³ is the same in action as the one previously described.

The operating member or plate D⁴ upon 5 the inner door is the same as the one shown in Fig. 1 and when the outer door is closed, engages the inclined edge D⁵ of the latch and depresses the inner end of the latch and raises the outer end, D⁶ so as to release the 10 outer door. As soon as the outer door is released, the guard D³ will fall and prevent the latch from falling into the catch until the outer door is opened. When the outer door is again closed, the latch will engage 15 the catch below the guard and lock the outer door again.

The operating member or plate D⁴ is pivoted upon a base D⁷ so that if it passes behind the latch, it will swing on the return 20 movement and permit the inner door to open. The same is true of the operating member shown in Fig. 1.

Bolts or catches of any convenient sort can be employed to keep both the doors 25 closed and when the inner one is locked, there is no danger of intrusion if the outer door should be left open.

An important advantage found in the use 30 of the pivoted operating plates C' and D⁴ is that it can be turned back out of possible engagement with the latch member as shown in Fig. 3. When placed in this position, it is not possible to open the outer door after 35 the inner door has been closed, so that no deliveries can be made while the occupants

of the house are away or do not wish to have deliveries made.

Having described the invention what I claim as new and desire to secure by Letters Patent is:—

In a safety wall receptacle, a casing, outer and inner doors therefor, a keeper having a vertical opening and mounted upon said outer door, a pivoted guard adapted to fall over said vertical opening, a latch member pivoted upon one side wall of said casing and provided with a latch extremity adapted to engage with the vertical opening in said keeper when the outer door is closed and to pass horizontally under said guard, and an operating member for said latch member, said operating member pivotally secured upon the inner face of said inner door, said latch member provided with a lateral extension adapted to be engaged by said operating member when the inner door is shut and depress the same; said operating member constructed to pass by said lateral extension after depressing the same and a stop means on said inner door preventing said operating member from swinging on its pivot when the inner door is closed but releasing the same when the inner door is opened.

In testimony whereof, I hereunto set my hand this 10th day of July, 1918.

WILLIAM J. SLOAN.

In presence of—

R. W. JEREMIAH,
W. M. MONROE.
